SIGNORS TO NACHOD & UNITED STATES SIGNAL CO., INC.

TROLLEY RAILWAY SIGNAL SYSTEM

Application filed June 25, 1928. Serial No. 288,133.

Our invention relates to electrically operated signals primarily intended for use on railways having electrically operated trolley cars wherein the motive current is supplied by means of a traveling current collector.

It is the object to produce a signal system which is automatically controlled by the movement of the car.

One object of our invention is to produce a system that works irrespective of the car using "power" or not, the system as herein-after described.

Another object of our invention is to provide a system that will employ trolley contactors of the normally closed type providing a much safer control system as herein-after more fully disclosed.

Another object of our invention is to provide a system in which independent cooperating means are employed to affect the displaying of the signal indications.

Another feature of our invention is to provide a safe control system embodying relays and circuit of much simpler nature than heretofore used in combination with electrically controlled trolley cars. This feature is highly desirable for production and service.

Our invention resides in a new and novel combination, the construction and relation of various electrically operated switches, circuits and other parts hereinafter more fully described and disclosed in the drawing.

In the drawing accompanying our specification:

Fig. 1 is a schematic drawing disclosing the general principles involved in employing normally closed trolley contactors.

Fig. 2 is a schematic drawing showing the arrangement of parts and circuits of the system in a normal condition of a modified circuit developed along the same principles involved in Fig. 1, but affording a greater degree of safety and protection. These principles of safety and protection are taken care of in the disclosure of our invention.

Our invention is intended primarily with use of those cars which are operated by means of an overhead trolley wheel or current collector W mounted on the car by means of a

trolley pole P, although it may be operated by cars in which current is supplied thereto by other means, such as a third rail and a shoe current collector. In the system shown in Fig. 1, the letter T represents a trolley wire or conductor. Positioned adjacent the trolley conductor are normally closed trolley contactors S and C which are equipped with mechanically operated deflecting strips A and D respectively. The normally closed trolley contactor S is equipped with a mechanical deflecting strip A which is to be engaged by a trolley wheel W. Secured to this deflecting strip is a contact arm B carrying a contact 1 which is connected to the trolley conductor T by flexible wire 14. Contact 1 is normally making contact engagement with contact 2 which is connected to coil RS of the controlling relay R by wires 3 and 3a, through lamp L1. The other normally closed contactor C that we employ is similar to S and has a mechanical deflecting strip D carrying a contact arm E secured thereto carrying the contact 7, and is connected to the trolley conductor T by flexible wire 15. Contact 7 is normally making contact engagement with contact 8 which is connected to the normally open back contact 10 of relay R by wire 9. The normally energized control relay R that we employ is equipped with an operating coil RS and armature F, and two insulated normally open back contacts 10 and 11. One coil terminal of coil RS is connected to lamp L1 by wire 3a, the other coil terminal of coil R is a common connecting point for wires 5 and 4, wire 5 connecting the armature F of relay R and wire 4 connecting the resistance unit RU, the other terminal of resistance unit RU being connected to the ground G by wire 6. The normally open back contacts 10 and 11 of relay R are used in displaying the signal L when the armature F is released, and in controlling the deenergization of the coil RS of relay R, contact 11 being connected to the signal lights L by wire 12, back contact 10 being connected to contact 8 of the normally closed contactor C by wire 9.

When the current collector of trolley wheel W engages the normally closed trolley con-

tactor S, the deflecting strip A is raised into the position A1 shown by the dotted lines A1, which in turn, effects a movement of the contact arm B to the position B1, as shown by the dotted lines B1, and normally closed contact 1 disengages contact 2 and moves to the position shown by 1a. This movement effects an opening of the circuit of the coil RS by opening the normally closed circuit 5 of the coil RS of relay R that was established through contacts 1 and 2 feeding from the trolley conductor R, through flexible wire 14, contact arm B, contact 1, contact 2, wire 3, lamp L1, wire 3a, coil RS of relay R, wire 4, resistance unit RU, wire 6 to ground G, and the armature F was raised and removed from contact engagement with the back contacts 10 and 11, opening the circuit 10 of the signal lights L established through the contact 10. Instant to the establishment of the circuit through the coil RS of signal, lamp L1 was displayed thereby restoring the system to a normal operating condition. It 15 will be noted that it was not a requirement for the current collector W to make electrical contact engagement with strips A and D respectively to effect the desired operation of the operating relay R used in the system. It is the purpose of the above description to show how two normally closed trolley contactors can be used to produce a subsequent deenergization and an energization of an operating coil respectively, one normally 20 closed contactor being for the establishment of the feeding circuit to effect an energization of the coil and the other normally closed trolley contactor being used to provide a shunt for the coil RS only after its armature has 25 been released to effect a deenergization of the coil. The opening of this circuit de-energized the coil RS and the armature F was released and fell into contact engagement with the normally open back contacts 10 and 30 11, and a shunt on the coil RS was established feeding from the normally closed contact C, feeding from trolley conductor T, through wire 15, contact arm E of trolley contactor C, contact 7 of trolley contactor C, contact 35 8 of trolley contactor C, wire 9, back contact 10 of relay R, armature F of relay R, wire 5, wire 4, through resistance unit RU to ground G through wire 6. Instant to the establishing of this circuit a second circuit was estab- 40 lished from the normally closed contactor C feeding from the wire 9, as heretofore described, through back contact 10 of relay R, armature F, back contact 11, wire 12, through signal light L, wire 13 to ground G, and the signal lights L were displayed. As soon as 45 the current collector W disengaged the normally closed trolley contactor S it was restored to its normal position and contacts 1 and 2 were brought into contact engagement but no circuit could be established through the coil RS as it remained shunted by the circuit feeding from the normally closed trolley contactor C, thus the armature F remained in its assumed released position and the signal lights L continued to display. 50 After the current collector W traveled a certain predetermined distance as regulated by the existing operating conditions, wherein the signal system might be employed, it came into engagement with the normally closed trolley contactor C. As soon as the current collector W engaged the normally closed trolley contactor, the deflecting strip D was raised to the dotted position D1 as shown, 55 and the contact arm E was moved to the position shown by the dotted lines E1, disengaging the normally closed contacts 7 and 8 by moving the contact 7 to the position shown by 7a. The opening of this circuit 60 removed the shunt on the coil RS of relay R that fed from the trolley conductor R through wire 15, contact arm E, contact 7, contact 8, wire 9, back contact 10 of relay R, armature F of relay R, wire 5, wire 4, re- 65 sistance unit RU, wire 6 to ground G, and

the coil RS of relay R was immediately energized by a flow of current feeding from the normally closed trolley contactor S, feeding from the trolley conductor T through wire 14, contact arm B, contact 1, contact 2, wire 3, signal lamp L1, wire 3a, coil RS of relay R, wire 4, resistance unit RU, wire 6 to ground G, and the armature F was raised and removed from contact engagement with the back contacts 10 and 11, opening the circuit 70 of the signal lights L established through the contact 10. Instant to the establishment of the circuit through the coil RS of signal, lamp L1 was displayed thereby restoring the system to a normal operating condition. It 75 will be noted that it was not a requirement for the current collector W to make electrical contact engagement with strips A and D respectively to effect the desired operation of the operating relay R used in the system. It is the purpose of the above description to show how two normally closed trolley contactors can be used to produce a subsequent deenergization and an energization of an operating coil respectively, one normally 80 closed contactor being for the establishment of the feeding circuit to effect an energization of the coil and the other normally closed trolley contactor being used to provide a shunt for the coil RS only after its armature has 85 been released to effect a deenergization of the coil. 90

In Fig. 2 the relay system is amplified so that a greater degree of flexibility and safety might be obtained. The principles involved 100 in the contactor circuit described in Fig. 1 being still retained with the exception that a series objection of the system as shown in Fig. 1 is overcome; that is, it will be noted by reference to Fig. 1 that if the signal is set and the coil RS is shunted by the path feeding from the normally closed trolley contactor C through wire 9, an opening of this circuit would render the signal cleared and the desired caution or danger signal would be removed wherein if this same condition would exist in the system disclosed and described in Fig. 2, no change would occur in the signal indication until a complete cycle had been completed at the clearing contactor; 110 that is, an intermittent opening and a subsequent reclosing of the circuit. 115

In the system shown in Fig. 2 separate and independent means are employed in the trolley contactor and the signal circuits to produce the separate desired operations although they have distinctively interlocked operating functions, relay R of the system being controlled by the normally closed trolley contactors, and relay N being controlled by relay RS to control the displaying of the signal lights. The operating coils of relay R and relay N have independent feeding sources but a common return through the resistor RU to ground G, a circuit for the coil RS 120

of relay R being established through contacts 1 and 2 of the normally closed contactor S, feeding from the trolley conductor T through flexible wire 19, contact arm B, contact 1, contact 2, wire 3, coil RS of relay R, wire 7, through wire 4, resistance units RU to ground G, through wire 6. A circuit for the coil NS of relay N being established from the normally closed contactor C through contacts 22 and 23 feeding from the trolley conductor T through flexible wire 20, contact arm E, contact 23, contact 22, wire 21, wire 11, coil NS of relay N, wire 10, front contact 8 of relay R, armature F of relay R, wire 4, resistance units RU, wire 6 to ground G.

It will be noted that the signal lamps L1 and L have an independent control and feed as shown in the drawing, the control being the armature F1 of relay N and the separate feed being established from the trolley conductor T through wire 5, armature F1 of relay N, normally closed front contact 12 of relay N, when the armature is in the raised position, wire 14, signal lamps L1, wire 17, wire 18 to ground G. When the armature F1 of relay N is released it will make contact engagement with the back contact 13 and the signal lights L will be displayed, a circuit being completed from the trolley conductor T, through wire 5, armature F1 of relay N, back contact 13 of relay N, wire 15, signal lamps L, wire 16, wire 18 to ground G. It will be noted in the control system, when the system is in the set condition, coil RS is shunted by a feed from the normally closed trolley contactor C, and the circuit of relay NS of relay N is opened by disengagement of armature F of relay R and the normally closed front contact 8 of relay R.

When the current collector W engages the normally closed trolley contactor S, the deflecting strip A is raised to the position shown by A1 and the contact arm B is moved to the position shown by B1 and the contact 1 disengages the contact 2 and moved to the position shown by 1a. The opening of contacts 1 and 2 opened the feed circuit for the normally energized control relay R by opening the feed that fed from the trolley conductor T through flexible arm B, contact 1, contact 2, wire 3, coil RS of relay R, wire 7, wire 4, resistance unit RU, wire 6 to ground G and the coil RS was deenergized and the armature F was released and brought out of contact engagement with the front contact 8 of relay R, and brought into contact engagement with the back contact 9 of relay R. Instant to the contact established by armature F of relay R, and back contact 9 of relay R, a shunt was provided for the coil RS of relay R, feeding from the normally closed trolley contactor C, feeding from the trolley conductor T, through flexible wire 20, contact arm E, contact 23, contact 22, wire 21, contact 9, armature F of relay R, wire 4, resistance units RU, wire 6

to ground G. The releasing of armature F of relay R, opened the ground return circuit for coil NS of relay N that was completed through armature F of relay R, and front contact 8 of relay R, and armature F1 of relay N was released and brought into contact engagement with back contact 13 of relay N, thereby removing the signal light indications L1 that were displayed by the circuit that was completed through armature F1 of relay N, and front contact 12 of relay N, and the signal lights L were displayed by a circuit being completed from the trolley conductor T, through wire 5, armature F1 of relay N, back contact 13 of relay N, wire 15, signal lights L, wire 16, wire 18, to ground G.

As soon as the current collector W disengaged the trolley contactor S, contact 1 returned into contact engagement with the contact 2, but no circuit was completed at this point as the coil RS of relay R remained shunted by the feed that was established from the normally closed contactor C through the back contact 9 and armature F of relay R. After the current collector had traveled a certain predetermined distance as is regulated by the existing conditions, wherein the signal system might be used, it came into contact engagement with the normally closed contactor C, and the deflecting strip D was raised into the position shown by D1. The movement of the deflecting strip D caused a movement of the contact arm E shown by the position E1, and a disengagement of the normally closed contacts 22 and 23 was effected by a movement of contact 23 to the position shown by 23a. The opening of contacts 22 and 23, removed the shunt of coil RS of relay R, and the coil RS was energized by a flow of current from the normally closed trolley contactor S, feeding from the trolley conductor T through flexible wire 19, contact arm B, contact 1, contact 2, wire 3, coil RS of relay R, wire 7, wire 4, resistance unit RU, wire 6 to ground G, and the armature F of relay R was removed from contact engagement with the back contact 9 and brought into contact engagement with the front contact 8. It will be noted at this point that the armature F of relay R was brought into contact engagement with the front contact 8 thereby completing the ground return for the coil NS through contact 8 and armature F, but the coil NS of relay N was not energized and no change in the signals displayed resulted, due to the fact that the current collector W continued to engage the normally closed trolley contactor C, holding the feed circuit for coil NS open.

As soon as the current collector W disengaged the normally closed trolley contactor C, however, contact 23 returned into contact engagement with contact 22 and the feed circuit for coil NS of relay N was established by a flow of current from the trolley conductor T, through flexible wire 20, contact arm E, con-

tact 23, contact 22, wire 21, wire 11, coil NS of relay N, wire 10, front contact 8 of relay R, armature F of relay R, wire 4, resistance unit RU, wire 6 to ground G, and the armature F1 was removed from contact engagement with the front contact 12 of relay N, and brought into contact engagement with the front contact 12 of relay N, thereby removing the indication of signal lights L and effecting a display of the signal lights L1 by the establishment of a circuit feeding from the trolley conductor T, through wire 5, armature F1, front contact 12 of relay N, wire 14, signal lights L1, wire 17, wire 18 to ground G. The restoring of the relays N and R to the normal condition, placed the system in a condition wherein a following car would receive the proper indication and be able to operate the relays in the same manner as heretofore described.

There are, of course, modifications and arrangements of the parts which may be made from that shown in the above disclosure and which will still fall within the scope of our invention.

We claim:

1. In an electrically operated signal system for an electric railway, comprising a trolley conductor, a current collector, a source of current, normally closed circuit trolley contactors having electrical circuits associated therewith, and a circuit including a plurality of signal lamps arranged to display desired signal indications, said contactors being so arranged as to be mechanically engaged by a current collector, control relays affected by the opening of the said trolley contactors, each relay being provided with an operating coil and a trolley contactor, means whereby one group of signal indications are displayed when one contactor circuit is opened and retained displayed until another one of the said trolley contactor circuits is opened and subsequently closed.

2. In an electrically operated signal system for an electric railway, comprising a trolley conductor, a current collector, a source of current, normally closed circuit trolley contactors having electrical circuits associated therewith, and a circuit including a plurality of signal lamps arranged to display desired signal indications, said contactors being so arranged as to be mechanically engaged by a current collector, control relays responsive to the opening of the said trolley contactors, each relay being provided with an operating coil and a trolley contactor, one relay to be controlled by a trolley contactor to affect a second relay controlling the said signal indications.

3. In an electrically operated signal system for an electric railway, comprising a trolley conductor, a current collector, a source of current, normally closed circuit trolley contactors having electrical circuits associated

therewith, said contactors being so arranged as to be mechanically engaged by a current collector, control relays responsive to the opening of the said trolley contactors, each relay being provided with an operating coil and a trolley contactor, one relay to be controlled by the trolley contactors to affect a second relay, said second relay being so arranged that an opening of any circuit in the control system will render the said relay inoperative.

4. In an electrically operated signal system for an electric railway, comprising a trolley conductor, a current collector, a source of current, normally closed circuit trolley contactors having electrical circuit associated therewith, said contactors being so arranged as to be mechanically engaged by a current collector, control relays affected by the opening of the said trolley contactors, each relay being provided with an operating coil and a trolley contactor, said relay coils having independent feed sources from each respective trolley contactor and provided with a common ground return thru a resistor, means affected thru one of the branch feeds to retain the contactor control relays de-energized.

5. In an electrically operated signal system for an electric railway, comprising a trolley conductor, a current collector, a source of current, normally closed circuit trolley contactors having electrical circuits associated therewith, said contactors being so arranged as to be mechanically engaged by a current collector, control relays affected by the opening of the said trolley contactors, each relay being provided with an operating coil and a trolley contactor, said relay coils having an independent feed and a common ground thru a resistor, means affected by one of the branch feeds to retain the contactor control relays de-energized until the said feed connection has been opened and subsequently closed, wherein the signal control relays will be restored to their normally energized condition.

6. In an electrically operated signal system for an electric railway, comprising a trolley conductor, a current collector, a source of current, normally closed circuit trolley contactors having electrical circuits associated therewith, said contactors being so arranged as to be mechanically engaged by a current collector, normally energized control relays, one of said relays affected by the opening of the said trolley contactors to control a second relay, each relay being equipped with a coil and an armature operating between contacts, means whereby one of said relay coils is energized through a heavy current flow when its armature is in the de-energized position and a lesser current flow when its armature is in its energized position.

7. In an electrically operated signal system for an electric railway, comprising a

5 trolley conductor, a current collector, a source of current, normally closed circuit trolley contactors having electrical circuits associated therewith, said contactors being so arranged as to be mechanically engaged by a current collector, a plurality of signal lamps, electrical circuits therefor, normally energized control relays affected by the opening of the said trolley contactors, one relay 10 to be controlled by the trolley contactors to affect a second relay controlling the said signal indications, means operative to retain the first said relay deenergized through the application of a shunt after one of the said 15 trolley contactors is engaged.

8. In an electrically operated signal system 20 for an electric railway, comprising a trolley conductor, a current collector, a source of current, normally closed circuit trolley contactors having electrical circuit associated therewith, said contactors being so arranged as to be mechanically engaged by a current collector, a plurality of signal lamps, electrical circuits therefor, normally energized 25 control relays affected by the opening of the said trolley contactors, one relay to be controlled by the trolley contactors to affect a second relay controlling the said signal indications, means operative to retain the first 30 said relay deenergized through the application of a shunt after one of the said trolley contactors is engaged, and means to restore the said relay to its normal energized condition when another one of the said trolley 35 contactors is engaged.

9. In an electrically operated signal system 40 for an electric railway, comprising a trolley conductor, a current collector, a source of current, normally closed circuit trolley contactors having electrical circuits associated therewith, said contactors being so arranged as to be mechanically engaged by a current collector, normally energized control relays affected by the opening of the said trolley 45 contactors, each relay being provided with an operating coil, armature and a trolley contactor, said relay coils normally having independent feed sources from each respective trolley contactor and provided with a common ground return through a resistor, means affected by the armature of one of the said relays to include the operating coil of another one of said relays when energized.

10. In an electrically operated signal system 50 for an electric railway, comprising a trolley conductor, a current collector, normally closed circuit trolley contactors, and a circuit including a plurality of signal lamps arranged to display desired signal indications, said contactors being so arranged as to be mechanically engaged by a current collector, a control relay affected by the opening of the said trolley contactors, means whereby one signal indication is displayed 55 when one contactor circuit is opened and re-

tained displayed until another one of the said trolley contactor circuits is opened.

11. In an electrically operated signal system 60 for an electric railway, comprising a contactor, a current collector, normally closed circuit contactors, said contactors being so arranged as to be mechanically engaged by a current collector, a plurality of signal lamps, electrical circuits therefor, a normally energized control relay affected by the opening of the said trolley contactors, means operative to retain the said relay deenergized through the application of the shunt after one or the said trolley contactors 65 is engaged.

12. In an electrically operated railway signal system, comprising a moving vehicle, normally closed circuit controlling contactors, a plurality of signal lamps, electrical circuits therefor, said contactors being so arranged as to be mechanically engaged by the moving vehicle, control relays affected by the opening of the said contactors, each relay being provided with an operating coil and a contactor, means whereby one signal indication is displayed when one contactor circuit is opened and retained displayed until another one of the said trolley contactor circuits is opened.

13. In an electrically operated railway signal system, comprising a moving vehicle, normally closed circuit controlling contactors, a plurality of signal lamps, electrical circuits therefor, said contactors being so arranged as to be mechanically engaged by the moving vehicle, control relays affected by the opening of the said contactors, each relay being provided with an operating coil and a contactor, means whereby one signal indication is displayed when one contactor circuit is opened and retained displayed until another one of the said trolley contactor circuits is opened, and subsequently closed.

14. In an electrically operated railway signal system, comprising a moving vehicle, normally closed circuit controlling contactors, a plurality of signal lamps, electrical circuits therefor, said contactors being so arranged as to be mechanically engaged by the moving vehicle, a control relay affected by the opening of the said contactors, means whereby one group of signal indications are displayed when one contactor circuit is opened and retained displayed until another one of the said contactor circuits is opened and subsequently closed.

15. In an electrically operated railway signal system, comprising a moving vehicle, normally closed circuit controlling contactors, said contactors being so arranged as to be actuated by the moving vehicle, control relays responsive to the opening of the said contactor circuits, each relay being provided with an operating coil and a contactor, one relay to be controlled by the contactors to

affect a second relay, said second relay being so arranged that an open of any circuit in the control circuit will render said relay inoperative.

16. In an electrically operated signal system, comprising normally closed controlling switches having a circuit including a plurality of signal lamps arranged to display desired signal indications, control relays affected by the opening of the said switches, each relay being provided with an operating coil and a controlling switch, means whereby one group of signal indications are displayed when one controlling switch circuit is intermittently opened and retained displayed until another one of the said controlling switch circuits is opened and subsequently closed.

In testimony whereof we affix our signatures.

SAMUEL S. STOLP.
